UNITED STATES PATENT OFFICE.

ROBERT A. HOUSTON, OF FORT DODGE, KANSAS.

BROOM.

1,157,108.

specification of Letters Patent.

Patented Oct. 19, 1915.

Application filed July 28, 1915. Serial No. 42,293.

To all whom it may concern:

Be it known that I, ROBERT A. HOUSTON, a citizen of the United States, residing at Fort Dodge, in the county of Ford and State of Kansas, have invented a certain new and useful Improvement in Brooms, of which the following is a specification.

My invention relates to improvements in brooms.

10 The object of my invention is to provide a broom of novel construction, and which will permit of the ready detachment from the handle of a worn out brush head and of the substitution therefor of a new brush head.

A further object of my invention is to provide a broom in which the brush head and the holder therefor, may be sold separately as distinct articles of manufacture.

20 Still another object of my invention is to provide a brush head for a broom comprising straws attached to the stalks and bound together, thereby reducing the liability of straws becoming detached, as often occurs 25 with the ordinary broom in which the straws are cut from the stalks.

My invention provides still further a novel holder provided with releasable means for detachably retaining a brush head 30 therein.

The novel features of my invention are hereinafter fully described and claimed.

In the accompanying drawing, which illustrates the preferred embodiment of my 35 invention, Figure 1 is a side elevation of my improved broom. Fig. 2 is a vertical sectional view of the same on the line 2—2 of Fig. 1, some of the parts being shown in elevation. Fig. 3 is a perspective view of

40 the brush head holder, showing the clamping springs and ring in the released positions, a portion of the handle and part of the socket member being broken away. Fig. 4 is an enlarged horizontal sectional view on the line 4—4 of Fig. 1. Fig. 5 is a 45 perspective view of my improved brush head. Fig. 6 is an elevation of one of the broom corn heads which forms part of the brush head.

50 Similar reference characters designate similar parts in the different views.

1 designates an ordinary broom handle having a reduced lower end fitted in and secured to an oblong block 2, which is fitted 55 within and is secured to a socket member 3 having the shape of a flattened hollow cone.

The block 2 is preferably of wood. The socket member 3 is preferably formed of suitable sheet metal, such as brass, steel or copper. The socket member 3 projects below the block 2, thereby forming a socket which is adapted to receive therein a detachable brush head, such as is shown in Fig. 5. The brush head preferably consists of a plurality of broom corn heads, one of which is shown in Fig. 6, and the straws of which, designated by 4, are left attached to portions of the stalks 5. The broom corn heads are held bound together by means of a plurality of horizontal bands 6, preferably of sheet metal. The upper end of the brush head is of a form which will neatly fit in the socket provided in the lower end of the socket member 3. As a means for detachably retaining the brush head in the socket member 3, I provide two V-shaped clamping members 7, preferably of spring wire. The free ends of the members 7 are inwardly turned and are adapted to respectively enter holes 8 provided respectively in opposite sides of the lower band 6. The upper ends of the V-shaped clamping members 7 are secured, preferably pivotally, to the handle 1 by means of a staple 9 which extends through the handle 1 and between the arms 85 of said V-shaped members, the ends of the staple being inserted in opposite sides of the handle 1 and embracing the upper ends of the clamping members 7. Slidably mounted on the handle 1 is a ring 10, preferably elliptical, and adapted to slide over the arms of the clamping members 7, Figs. 1 and 2, thereby releasably holding the in-turned ends of said members in the holes 8 respectively.

95 The brush head is preferably provided, below the bands 6, with a plurality of transverse seams 11, disposed one above the other and corresponding in number to the length of straw and size of broom head. When 100 the straw wears off, the stitches of the lowermost seam may be cut and unraveled, thus renewing the pliability of the brush. As the straws wear off still more, the next seam above may be unraveled. This may be repeated until all of the seams have been removed. This construction greatly increases the period of usefulness of the brush head. When a brush head has become worn out, the ring 10 is slipped to the position shown 110 in Fig. 3, and the members 7 are disengaged from the brush head, whereupon the latter

will fall out of the socket member 3. A new brush head may then be inserted and engaged with the clamping members 7, the ring 10 being slipped over said members to 5 the position shown in Fig. 1. As the straws are attached to the stalks 5, they will not loosen from the brush head as they do in the ordinary broom. Similar lengths of straws are used for different sizes of brooms, 10 thus enabling the utilization of all lengths of broom corn heads. As shown in Fig. 3, the wires 7 are preferably curved with the convex sides out, thereby enabling the ring 10 to be securely held in the locked position and to cause said wires to exert a spring 15 pressure against the brush head so as to be reliably held engaged therewith.

I do not limit my invention to the structure shown and described, as modifications, 20 within the scope of the appended claims, may be made without departing from the spirit of my invention.

What I claim is:

1. In a broom, a handle, a socket member 25 secured to one end thereof, a brush head adapted to be detachably mounted in said socket member, a clamping device secured to the handle and having means for engaging and holding the brush head in said socket 30 member, and a ring slidably engaging the handle and adapted when moved thereon to the proper position to hold the clamping device engaged with the brush head.

2. In a broom, a handle, a socket member 35 secured to one end thereof, a brush head adapted to be detachably mounted in said socket member, a spring clamping member attached to the handle and having means for engaging the brush head and holding 40 it in said socket member, and a ring slid-

ably mounted on the handle and adapted to slide onto the clamping member so as to hold the clamping member engaged with the brush head.

3. In a broom, a handle, a socket member 45 secured to one end thereof, a brush head adapted to be detachably mounted in said socket member, a V shaped clamping member secured to the handle and having the free ends of its arms inwardly extending 50 and adapted to enter the brush head and retain it in said socket member, and means for releasably holding said V shaped clamping member engaged with said brush head.

4. In a broom, a handle, a socket member 55 secured to one end thereof, a brush head adapted to be detachably mounted in said socket member, a V shaped clamping member secured to the handle and having the free ends of its arms inwardly extending 60 and adapted to enter the brush head and retain it in said socket member, and a ring slidable on the handle onto and off from the arms of said V shaped member and adapted when slid to the proper position 65 to releasably hold said arms engaged with said brush head.

5. In a broom, a handle, a socket member secured thereto and adapted to receive a brush head, a curved spring clamping member pivoted at its upper end to the handle and having an inwardly turned lower end adapted to engage the brush head, and a ring slidably mounted on the handle and adapted to embrace and hold said clamping 70 member in the brush head engaging position.

In testimony whereof I have signed my name to this specification.

ROBERT A. HOUSTON.
